UNITED STATES PATENT OFFICE.

NATHANIEL H. BENTON AND HERBERT L. GODDING, OF MADISON, WISCONSIN.

SULKY-HARROW.

SPECIFICATION forming part of Letters Patent No. 372,357, dated November 1, 1887.

Application filed March 5, 1887. Serial No. 229,761. (No model.)

To all whom it may concern:

Be it known that we, NATHANIEL H. BENTON and HERBERT L. GODDING, citizens of the United States, residing at Madison, in the county of Dane and State of Wisconsin, have invented certain new and useful Improvements in Sulky-Harrows; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to harrows, and has for its object the production of a complete and efficient sulky-harrow, which shall be capable of such changes as will enable us to use two or more horses abreast, as may be desired, by closing or spreading a double pole, and which shall possess means for accurately adjusting and securely fixing the depth of the harrow in the ground. In addition to these two leading objects, many minor but useful novel constructions of parts and improved results are attained, some of which may be mentioned, as follows: the novel means for uniting the double pole, the novel means for spreading or separating the same, the draft attachment, the means for securing the levers for controlling the ends of the harrow-frames, the means for uniting the harrow-frames, the novel position in which the harrow-frames are held, and the novel brace for the axle, and a novel form of holding means for the harrow-teeth, and means for adjusting the seat.

The invention herein set forth is an improvement upon an application for patent on the same character of invention which has recently been allowed to us.

The accompanying drawings illustrate what we consider the best means for carrying our invention into practice.

Figure 1 is a plan view of the harrow, showing the double tongue united in front as used for two horses. Fig. 2 is a plan view of the tongue or pole spread as is done when three or four horses are used. Fig. 3 is a side elevation of the machine with one wheel removed. Fig. 4 is a rear elevation of the axle. Fig. 5 is a plan view of one of the harrow-beams, showing the means for attaching the teeth.

Fig. 6 is a side elevation of Fig. 5. Fig. 7 is a side elevation of the adjusting means for the frame-levers. Fig. 8 is a detail showing a portion of said adjusting means.

Similar letters of reference indicate corresponding parts in all the figures where they occur.

A is the axle, and B the tongue or pole. The axle is braced in a peculiar manner, as will hereinafter be explained. The pole is composed of two parts, each of which is marked B. Each of the said parts is secured to the axle by pivots b b, and is provided at its outer end with projecting plates b' b', perforated as shown, through which perforations a hook upon the yoke is inserted, and the two parts of the pole are thus united at the front end. Diagonal braces b' b' extend from member to member of the pole at about the hitching-point. The forward ends of these braces are movable, and are set farther up the pole to bring the front ends thereof together, or are set farther back upon the pole to spread the parts or members of the pole and cause them to stand about parallel with each other, as shown in Fig. 2. When they are thus spread, a double yoke will be used, as shown in Fig. 2. A hook or hanger, b'', may be placed at the point of crossing of the two braces and extend down to sustain the doubletree. At a point just back of the said braces and beneath the pole members are attached braces or brackets B' B', to which the front ends of the levers C C are pivoted. These levers extend back under the pole members, where they are provided with stirrups for the feet of the driver. Between the front and rear ends the said levers have the chains for raising and lowering the ends of the harrow-frames, as will be more fully explained hereinafter. They also have pivoted to them the upright arms D D, which pass through plates d d on the rear portion of the pole members B B, and the said arms are provided with notches or notches, which are engaged by the said plates, and a spring, d', on each plate preserves the connection between the said arms and the plates. This notch in each of the arms is at just the proper point to drop the harrow-frames to the depth ordinarily required in pulverizing the soil, and which may be termed the normal position. An eccentric lever, E, pivoted upon the said pole members with a

spring, *e*, to keep it in engagement with the rack *E'*, bears with its curved or eccentric end upon each of the levers *C* and aids the arms *D* in sustaining the harrow-frames in the normal position when said lever *E* is properly set. In addition to this function the lever *E* can be and is used for making the adjustments required in raising and lowering the ends of the harrow-frames. It will be seen that the 10 said lever *E*, by being turned into an inclined position forward or backward, will depress or raise the levers *C*, and by the engagement with the rack *E'* will securely hold them in the said depressed or elevated position. This is 15 illustrated in Fig. 7, where the rear end of the levers *C* is elevated, which elevation will let the harrow run deeper.

It will be understood that the arms *D* are preferably made with the single notch to keep 20 them at the normal position only; but they may have notches at different heights to help to hold the harrow-frames in any adjustment. It will also be noticed that the weight of the 25 harrow-frames can be raised by foot-pressure upon the levers *C* and the strain upon lever *E* relieved.

Braces *F F*, extending from a point on the pole members in front of the axle to a point on the same in the rear of the axle, are dropped 30 under the axle and tend to stiffen the parts.

A longitudinal brace, *G*, is applied to the axle for the purpose of giving it strength by having the ends of the two members or part 35 of said brace *G* fastened over the ends of the axle on top, and bent under or down and engaged near or at the center of the axle by a transverse metal piece, *g*, which clamps the said brace-members and gives it great tension and adds great strength to the axle.

40 The seat (marked *H*) is supported on arms *h h*, which converge at the seat end and are spread out at the forward end and engaged in any desired one of a series of holes in the projections or brackets *h'*. The arms *h h* rest upon 45 the axle between the seat and the front connection, and by adjusting the front ends of the arms to different heights in the brackets *h'* the seat can be raised or lowered, as may be desired.

50 I I are the harrow-frames united by means of a rod, *I'*, which passes through ears *i i* on the ends of the beams of the frame. The frames I I are set at an oblique angle to each other and to the axle, so as to cause the beams of the 55 frames to slope backward from the point of union on the center of the machine. This position of the frames gives them the same qualities as the square harrow when hitched to a corner thereof, or of the double-A harrow, well 60 known in farming. The frames are held in substantially a uniform position laterally by means of the guide device *J*, which was shown and claimed in our previous application above referred to, while they are permitted to swing 65 in a line with the progression of the harrow by the same device.

A chain, *I''*, is attached near the outer end of each frame I, and after passing over rollers on the axle is attached to the foot-lever *C* in substantially the same manner shown and described in the said application. 70

A chain, *I'*, attached to about the center of the bar or rod *I*, is passed up over the adjusting cam-lever *I''*, substantially like that in the previous application. 75

The draft devices (marked *K*) are attached by means of chains *k* to the harrow-frames, and by chains *k'* to the brackets *B'*, and, as before stated, a hook or hanger, *b''*, may be employed to connect the said draft devices to the braces 80 *b'*, the hook or hanger *b''* being particularly intended for use when the draft device is not in use to keep it off the ground.

Teeth *L* are applied to the frame I by means of a crimped and angularly-molded piece of 85 metal, *L'*, which rests against the beam and a through hook or clamp, *l*, for holding the tooth and plate *L'* against the beam. The construction of the plate *L'* is such as to give a slight elastic quality to the device, and thus more 90 securely hold the teeth.

When three or four horses are used, a different evener and yoke are used. The yoke for three or four horses is shown in Fig. 2, where provision is made for the attachment of three 95 single yokes.

Having thus described our invention, what we claim, and desire to secure by Letters Patent of the United States, is—

1. In a harrow or analogous device, a pair 100 of pole members, *B B*, provided with the plates or parts *b'*, permanently secured to the pole members, and having the projecting perforate portions, as described, said projecting perforate portions serving to hold the pole members together by the insertion of a ring or hook, and also serving to receive the ring or hook of the yoke when the pole members are separated, said pole members being pivoted upon the axle, as set forth. 110

2. In a harrow or analogous device, the combination, with the pole members *B B* and means for uniting or separating them at the front ends, consisting of the plates *b*, secured to the said members, and having projecting portions with 115 holes or perforations therein, said projecting portions *b'* serving to hold the pole members together by the insertion of ring or hook, and also serving to receive the ring or hook of the yoke when the pole members are separated, 120 of the braces *b''*, movable, as described; and applied to the pole members near the axle of the device.

3. The combination, with the harrow-frames pivotally connected, as described, chains connecting the ends thereof with foot-levers, of 125 said foot-levers, and brackets set upon the under side of the pole members, to which brackets the fronts of the foot-levers are pivoted.

4. In a harrow, the combination, with the 130 adjustable frame, foot-levers for producing the adjustment, of the upright arms *D*, connected

to the foot-levers and passing through plates provided with springs for holding the said arms at a normal elevation.

5. The combination, with the foot lever or levers for regulating the harrow-frames, of the eccentric lever E and means for setting it, as described.

6. The combination, with the foot lever or levers, of the eccentric lever E, having its curved or eccentric end resting on the foot-lever, a rack, E', for engaging said lever, and a spring for preserving said engagement.

7. In a harrow, the combination, with the frame-beams, of the crimped and slightly-elastic plates L', the teeth L, and the through bolt 15 or hook l, all substantially as and for the purpose set forth.

In testimony whereof we affix our signatures in presence of two witnesses.

NATHANIEL H. BENTON.
HERBERT L. GODDING.
